[57] CLAIM

The ornamental design for a four wheeled cycle, as shown and described.

DESCRIPTION

FIG. 1 is a perspective view of a velocipede, showing our new design;

FIG. 2 is a right side elevational view thereof;

FIG. 3 is a top plan view thereof;

FIG. 4 is a front elevational view thereof;

FIG. 5 is a rear elevational view thereof; and,

FIG. 6 is a bottom plan view thereof.

The left side view is a mirror image of the right side elevation view shown in FIG. 2.
